FIG. 1

FIG. 2

FIG. 3

FIG. 1 is a right front perspective view of a paperboard blank feeder bar with longitudinally aligned and spaced feed clips showing our new design;

FIG. 2 is a right front perspective view of the feed clip elements of a modified form of the paperboard blank feeder bar with longitudinally aligned and spaced feed clips of FIG. 1, wherein the only difference over the feeder bar of FIG. 1 resides in the appearance of the feed clip element; and

FIG. 3 is a right front perspective view of the feed clip element of another modified form of the paperboard blank feeder bar with longitudinally aligned and spaced feed clips of FIG. 1, wherein the only difference over the

feeder bar of FIG. 1 resides in the appearance of the feed clip element.

We claim:

The ornamental design for a paperboard blank feeder bar with longitudinally aligned and spaced feed clips, substantially as shown and described.
